UNITED STATES PATENT OFFICE.

NOËL M. BUSH, OF MONTCLAIR, NEW JERSEY.

DESIGN FOR A RAIN-COAT.

46,244.

Specification for Design.

Patented Aug. 11, 1914.

Application filed June 1, 1914. Serial No. 842,321. Term of patent 7 years.

To all whom it may concern:

Be it known that I, NOËL M. BUSH, a citizen of the United States, residing at Montclair, in the county of Essex and State of New Jersey, have invented a new, original, and ornamental Design for Rain-Coats, of which the following is a specification, reference being had to the accompanying drawings, forming part thereof.

Figure 1 is a front elevation in perspec-

tive; and Fig. 2 is a similar view of the rear, showing my new design.

I claim:

The ornamental design for a rain coat, as shown.

NOËL M. BUSH.

Witnesses:

GEO. L. BEELER,
PHILIP D. ROLLHAUS.
